CANOE PADDLE

Filed Sept. 8, 1930

UNITED STATES PATENT OFFICE

HORACE B. HERRING, OF MEMPHIS, TENNESSEE

CANOE PADDLE

Application filed September 8, 1930. Serial No. 480,491.

The present invention relates to paddles, such as are used in propelling canoes and the like, and has for an object to provide a device of this kind which can be knocked down and packed away into a small space.

Another object of the present invention is to provide a device of this kind which can be quickly assembled, and when set up for use, will be rigid and strong, and will not rattle or vibrate.

Another object of the present invention is to provide a device of this kind, which has a blade foldable longitudinally, so that it can be put away into a comparatively small space.

A still further object of the present invention is to provide a device of this kind consisting of few parts, which are easily disassembled and adapted to be packed away in a suitable case along with the other camping supplies.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a paddle constructed according to the present invention.

Figure 2 is a fragmentary enlarged view partly in section with the parts of the paddle separated.

Figure 3 is a side elevation of a paddle with the parts knocked down ready to be stored away.

Figure 4 is a detail view showing the outer ends of the paddle frame separated.

Referring more particularly to the drawings, 10 represents the shank and is provided at its inner end with a handle 11 which is adapted to fit in the palm of the hand when the paddle is being used. The outer end of the shank is provided with the reduced shouldered portion 12, which is adapted to receive a ferrule 13, which is provided with a reduced externally threaded portion, which forms a stud 14.

An internally threaded socket 15 is provided in a coupling piece 16, and this socket

15 is adapted to receive the stud 14 when it is desired to assemble the paddle for use.

The coupling piece 16 may be formed of a metal block or other suitable material, and is preferably flared in width towards its outer end, so that the coupling piece will form substantially a continuation of the shank 10. The coupling piece 16 is provided at its outer end with the longitudinally extending slots 17, which converge towards their inner ends. The coupling piece 16 may be provided with set screws 18 at each side thereof for entering the slots 17.

The blade of the paddle consists of a pair of frame members 19, which, when fitted together, are adapted to have their outer ends overlap. The frame members 19 are provided at their inner ends with the arms 20, which converge towards their inner ends, and are adapted to be sprung apart, and inserted into the slots 17 of the coupling piece 16, in which they are held by the set screws 18.

The frame members 19 are covered by a body portion 21 of canvas or other suitable material, which is secured thereto by stitching 22 or in any other manner desired. The outer end of one of the frame members 19 is provided with a strap 23, which is adapted to receive the off-set tongue 24 of the other frame member to prevent the frame members from moving with respect to one another.

The outer end of one of the frame members 19 carries at its inner side a socket 25, which is adapted to receive a brace rod 26. This brace rod 26 lies at one side of the cover for the frames 19, and is adapted to prevent the cover from bulging outwardly when the paddle is in use. The brace rod 26 is provided at its inner end with an arm 27, which is adapted to be received in a socket 28 in the coupling piece 16.

The brace rod 26 also carries a pair of coupling plates 29, which are secured to the rod by a ring 30, or other suitable means. The frame members 19 also carry the inwardly and angularly extending brace rods 31, which have the tongues 32, which are adapted to be received into sockets 33 in the coupling plates 29.

When it is desired to use the paddle, the

stud 14 is threaded into the socket 15, and the arms 20 of the frames 19 are expanded until they register with the slots 17 in the coupling piece 16, whereupon they are slidably inserted into the slots 17, and the set screws 18 are then screwed against these arms 20, so as to retain the blade rigidly and securely to the coupling piece.

The arm 27 is also inserted into the socket 28 of the coupling piece. The blade is held in extended position by the brace arms 31, which are connected to the brace rod 26 through the coupling plates 29.

It will be obvious that various changes might be made in the construction, combination and arrangement of parts, which could be used without departing from the spirit of my invention, and I do not mean to limit the invention to such details, except as particularly pointed out in the claims.

Having thus described my invention, what I claim and desire to secure by Letters Patent of the United States is:—

1. A paddle comprising a shank, a blade consisting of a pair of frame members having their outer ends overlapping, means for releasably holding the outer ends of the frame members together, and a coupling piece for connecting the shank and blade together.
2. A paddle comprising a shank, a blade consisting of a pair of frame members having their outer ends overlapping, means for securing the outer ends of the frames together, a brace rod carried by the outer end of one of the frame members, coupling plates carried by said brace rod, and brace arms carried by the frame members, their free ends adapted to be received by the coupling plates.

HORACE B. HERRING.
